BATHTUB FOR INFANTS

Roberto Menghi, Milan, Italy, assignor to Smalterie Meridionali S.p.A., Casalnuovo di Napoli, Italy, an Italian joint-stock company

Application September 30, 1955, Serial No. 38,186

Claims priority, application Italy June 1, 1955

Term of patent 3½ years

(Cl. D4—4)

FIG. 1

FIG. 3

Fig. 1 is a perspective view of a bathtub for infants, showing my new design;

Fig. 2 is a side elevation; and

Fig. 3 is an end elevation taken from the right of Fig. 2.

The other side of the bathtub not shown is substantially like the side shown.

What I claim is:

The ornamental design for a bathtub for infants, as shown and described.
